UNITED STATES PATENT OFFICE.

CHARLES EDWARD CAMERON, OF COLLINGSWOOD, NEW JERSEY, ASSIGNOR TO WILLIAM A. MOONEY, HARRY J. LOOBY, JOHN B. CONNOLLY, AND CHARLES E. CAMERON, ALL OF PHILADELPHIA, PENNSYLVANIA, A COPARTNERSHIP TRADING AS LIGHTNING DEMOUNTABLE RIM COMPANY.

DETACHABLE WHEEL-RIM.

1,104,874.

Specification of Letters Patent. Patented July 28, 1914.

Application filed July 1, 1913. Serial No. 776,784.

To all whom it may concern:

Be it known that I, CHARLES E. CAMERON, a citizen of the United States, residing at Collingswood, in the county of Camden and 5 State of New Jersey, have invented certain new and useful Improvements in Detachable Wheel-Rims, of which the following is a specification.

The principal object of the present invention is to improve detachable rims by providing means which do not materially decrease the strength of the wheel and by which the rim can be rapidly and easily applied and removed and by which the rim is 15 held firmly and satisfactorily in place.

Another object of the invention is to provide for converting, at comparatively little cost, ordinary wheel rims into detachable wheel rims.

20 The invention will be claimed at the end hereof, but will be first described in connection with the embodiment of it chosen from among other embodiments for illustration in the accompanying drawings, in 25 which—

Figure 1, is a side view of a wheel, partly in section, embodying features of the invention. Fig. 2, is a side view, drawn to an enlarged scale and partly in section. Fig. 3, 30 is a transverse sectional view, and Fig. 4, is a side view.

In the drawings 1 is the detachable rim and 2 is the felly that is carried by the spokes 3. The felly 2 consists of a wooden 35 part or felly 4 and an encircling felly band or fixed rim 5. At suitable points around the wheel are provided locking devices which are all alike so that a description of one will be sufficient.

40 6 is a plate disposed in the plane of the wheel and provided with a base 7 disposed at a right angle in respect to it and with a notched tongue 8, narrower than the plate and disposed parallel with the base. The 45 base 7 and tongue 8 are disposed at right angles to the plane of the wheel and there is sufficient space between them to receive the spoke felly 2. The felly 4 is grooved at right-angles to the plane of the wheel where 50 it passes between the base 7 and tongue 8. The base 7 is attached to the detachable rim 1 as by means of rivets 9 and it extends only a part way across the felly 2, so that the felly

band or fixed rim 5 need not be cut clear through for its accommodation, but is simply notched. 10, is a housing generally oblong in shape and arranged in the plane of the wheel. This housing rests upon a plate 11 having flanges 12 and 13 which straddle the spoke felly 2. The flange 13 is provided 15 with ears 14 by means of which it is secured to the side of the felly 4 as by screws 15 and it is also provided with an opening 16 for the reception of the tongue 8. A spring 17, arranged in the housing 10 and fastened at 20 one end 18, carries at its other end a bolt 19. The shank 20 of the bolt 19 is connected pivotally with a cam or eccentric finger piece 21 having two cam faces 22, one at each side of the housing and arranged to operate on the 25 plate 11.

To remove the detachable rim from the fixed rim the cam finger pieces 21 are turned into the position shown at the top in Fig. 1, thus retracting the bolts 19 so that the detachable rim 1 can be pulled off laterally. The cam finger pieces 21 can then be put into the position shown in Fig. 2 and a detachable rim can be applied by simply inserting its tongues 8 through the openings 16 and 30 pushing it onto the fixed rim and in this operation the springs 17 yield and permit the bolts to snap into the grooves in the tongues, thus holding the detachable rim firmly to place.

Evidently the described device can be applied to existing wheels at comparatively little expense, since very little alteration has to be made in them for the purpose. The alteration consists principally in laterally 35 notching the fixed rim 5 for the accommodation of the base 7 and in fitting the flanges 12 and 13 to the felly and in notching the latter to permit it to pass between the base 7 and the tongue 8.

In use the parts are well protected from dirt, but they are so simple and comparatively massive that a reasonable amount of dirt or dust cannot interfere with their operation.

I do not desire to limit the invention further than the state of the art by reason of any terminology or language that I may employ, but

What I claim is:
Means for detachably connecting fixed

105

rims and detachable rims which comprise the combination of a plate provided with a right angularly disposed base of approximately half the width of the fixed rim and adapted for attachment to the detachable rim and provided intermediate of its top and bottom with a groove tongue parallel with the base and spaced therefrom for the accommodation of the felly and unnotched portion of the fixed rim, a housing provided with a base having flanges adapted to straddle the felly and whereof one is provided with an opening for the reception of the tongue and with attaching means, a spring

arranged in the housing and provided with 15 a bolt adapted to coöperate with the grooved tongue and with a shank, and a finger eccentric lever attached to the shank and adapted to permit the bolt to operate as a spring bolt and to hold the same in one position, 20 substantially as described.

In testimony whereof I have hereunto signed my name in the presence of two witnesses.

CHARLES EDWARD CAMERON.
